UNITED STATES PATENT OFFICE.

WILHELM SCHENKA, OF FORST, GERMANY.

LOOM-DOBBY.

1,159,999.

Specification of Letters Patent.

Patented Nov. 9, 1915.

Application filed June 30, 1915. Serial No. 37,362.

To all whom it may concern:

Be it known that I, WILHELM SCHENKA, a subject of the Emperor of Germany, residing at Forst, i. d. Lausitz, Mark Brandenburg, Germany, have invented certain new and useful Improvements in Loom-Dobbies, of which the following is a specification.

This invention has for its object to provide an improved loom dobbay of the type comprising two-armed, that is, intermediately fulcrumed, horizontal drawhooks which are connected directly to the heald levers or jack levers. Drawhooks of that kind have already been constructed by making one arm of the drawhook heavier than the other arm, so that when it was not raised, it engaged automatically with its knife. When however, the lighter arm of the drawhook had to engage its knife, and to remain securely in its engaged position, not only was it necessary to raise the heavier part of the drawhook, but the part that effected this raising, supported the heavier drawhook portion during the movement of the knife. That arrangement had the drawback that the raising of the heavier drawhook portion was not insured, especially its protracted support in its raised position. If the lighter drawhook portion did not come into engagement with its knife, or disengagement took place prematurely, then the most serious disturbances occurred in the working. Moreover the high speed of all power looms must be taken into consideration. The operation became still more uncertain when the raising of the heavier drawhook portion was effected by means of an independent intermediate member. Now those drawbacks are remedied by the improvements of the present invention according to which vertically movable pegs actuated by a lattice or peg barrel in the usual manner, are employed to raise the heavier drawhook portion outside of its shoulder that is designed to engage the knife, and that, after this raising, the heavier drawhook portion supported on its knife, takes over immediately after the commencement of the movement of the knife, the insuring of the engagement of the lighter drawhook portion with its knife, while completely relieving the peg of its load.

Reference is now to be had to the accompanying drawings, in which:

Figure 1 is a diagrammatic view of a loom dobbay embodying one form of the improve-

ments of the present invention, the parts thereof being shown in position for a closed shed. Fig. 2 is a similar view of the loom dobbay with its parts in position for an open

60

In the example shown, a_1 and a_2 are the heald levers or jacks to which the wires, straps or cords for the healds are connected. The heald levers a_1 and a_2 carry pivoted to them, the horizontal drawhooks b_1 and b_2 which are intended to coöperate with the knives c_1 and c_2 . The horizontal drawhooks b_1 and b_2 are constituted by arms d_1 , e_1 and d_2 , e_2 of which the arms e_1 and e_2 are the 70 heavier and are formed with extensions g_1 and g_2 beyond the shoulders f_1 and f_2 that are designed to engage the knife c_2 .

h indicates one of the vertically movable pegs operated by the lattice or peg barrel.

75

In Fig. 1, the knives c_1 and c_2 are shown pushed together as far as possible; this position corresponds to the closing of the shed. The lattice barrel then raises by its pegs a part of the horizontal drawhooks, for instance b_1 , so that the lighter end of the drawhook comes into engagement with the knife c_1 . The horizontal drawhooks for instance b_2 , hang with their heavier hook part e_2 downward, and engage therewith the 85 knife c_2 . The knives c_1 and c_2 now move apart; the engagement of the knife c_2 with the horizontal drawhook b_2 being insured by reason of the weight of the drawhook part e_2 . The engagement of the lighter 90 drawhook d_1 with the knife c_1 is insured by the circumstance that immediately the knives move apart, the heavier drawhook part e_1 (if the friction between the shoulder of the drawhook and the knife c_1 is not sufficient to keep these parts from relative movement) moves down upon the knife c_2 and remains permanently supported by this knife. It will be understood that the slight 95 downward movement of the part e_1 (if such occurs) is not sufficient to disengage the shoulder of the drawhook from the knife c_1 . The peg h has moved back immediately, and it does not come into injurious contact with the horizontal drawhook b_1 during the 100 movement of the latter. This is shown in Fig. 2.

What I claim is:—

1. In a loom dobbay the combination of 110 horizontal drawhooks pivoted directly to the heald or jack levers intermediate of the ends of said drawhooks, dobbay knives ar-

ranged adjacent to said drawhooks, projections on each side of the pivot of said drawhooks forming shoulders for engagement with said dobby knives, each of said drawhooks being heavier on one side of its pivot than on the other so as to tend to keep one of its shoulders out of engagement with its dobby knife and the other shoulder in engagement with its dobby knife, vertically 5
10 movable pegs adapted to engage the heavy ends of said drawhooks so as to raise same, and a lattice or peg barrel for operating said pegs and permitting any raised pegs to be lowered immediately after the commencement 15
15 of lateral movement of the knives, the disengaged ends of the corresponding drawhooks, if said ends are lowered, being brought into slidable contact with the adjacent dobby knife and the shoulders at the opposite ends maintained in engagement with their dobby knife throughout the lateral movement of the knives.

2. In a loom dobby the combination of horizontal drawhooks pivoted directly to the 20
25 heald or jack levers intermediate of the ends of said drawhooks, dobby knives arranged

below and adjacent to said drawhooks, downward projections on each end of said drawhooks forming shoulders for engagement with said dobby knives, each of said drawhooks being heavier on one side of its pivot than on the other so as to tend to keep the shoulder on the latter side out of engagement with its dobby knife and the shoulder on the former side in engagement 30
35 with its dobby knife, vertically movable pegs adapted to engage the heavy ends of said drawhooks so as to raise same, and a lattice or peg barrel for operating said pegs and permitting any raised pegs to be lowered immediately after the commencement of lateral movement of the knives, the heavy ends of the corresponding drawhooks, if said ends are lowered, being brought into gliding engagement with the adjacent dobby 40
45 knife and the shoulders at the lighter ends maintained in engagement with their dobby knife throughout the lateral movement of the knives.

In testimony whereof I have signed my name in this specification.

WILHELM SCHENKA.
